ICE FISHING BOX

Wayne E. Gay, Marshall, Mich.

Application January 31, 1955, Serial No. 34,291

Term of patent 14 years

(Cl. D67—4)

Figure 1 is a side perspective view of an ice fishing box embodying my design. The other side is the same except that there is no door or doorway;

Figure 3 is a side elevation thereof with the door in open position; and

I claim:

The ornamental design for an ice fishing box, substantially as shown and described.
